SURFACE ORNAMENTATION OF WALLS.

No. 18,430.

Patented July 3, 1888.

UNITED STATES PATENT OFFICE.

FREDERICK KOSKUL, OF WILLIAMSPORT, PENNSYLVANIA.

DESIGN FOR THE SURFACE ORNAMENTATION OF WALLS.

SPECIFICATION forming part of Design No. 18,430, dated July 3, 1888.

Application filed March 17, 1888. Serial No. 267,782. Term of patent 14 years.

To all whom it may concern:

Be it known that I, FREDERICK KOSKUL, of Williamsport, Lycoming county, Pennsylvania, have invented and produced a new and original Design for the Surface Ornamentation of Walls, &c., of which the following is a specification.

In the accompanying photograph, the figure represents my design in a single row.

- 10 Similar letters of reference indicate like parts.
- My design consists in the quadrangular elevation A, having on its face four inclined sur-

faces, B C D E. At the center of the said face is an elevation, F, having four convex sides, G H I J, and around said elevation appears a ledge or bead, K.

I claim—

The design for surface ornamentation of walls, &c., substantially as herein shown and described.

FREDERICK KOSKUL.
